SEWING MACHINE FOR APPLIQUÉS

Walter Harpham, Hartford, N. J., assignor to L. Nachman & Sons, a partnership comprising Louis Nachman, Joseph Nachman, and Jack Nachman, all of Philadelphia, Pa.

Application October 4, 1944, Serial No. 557,072

4 Claims. (Cl. 112—98)

1

My invention relates to sewing appliqués upon a fabric in order to provide an attractive appearance to the garment.

Heretofore, appliqués which are ornaments of one material affixed to the surface of another have been employed.

My invention provides appliqués of two symmetrically arranged tapes running in an irregular or regular configuration upon the surface of fabric; whereby the appliqués may be held by a plurality of spaced row of stitches.

It is an object of my invention to provide a sewing machine with mechanism whereby two symmetrical designs may be stitched to a fabric simultaneously.

Another object of my invention is to provide a sewing machine with mechanism whereby two symmetrical designs may be sewed upon a surface by a plurality of rows of stitches simultaneously.

Another object of my invention is a sewing machine with mechanism whereby two symmetrical designs may be sewed to a surface by a plurality of rows of stitches and whereby the designs may be changed by changing the mechanism.

Other objects of my invention are to provide an improved device of the character described, that is easily and economically produced, which is sturdy in construction, and which is highly efficient in operation.

With the above and related objects in view, my invention consists in the details of construction and combination of parts, as will be more fully understood from the following description, when read in conjunction with the accompanying drawing in which:

Fig. 1 is a front view of a sewing machine embodying my invention for sewing appliqués to fabric.

Fig. 2 is a rear elevational view of the sewing machine of Fig. 1.

Fig. 3 is an end view of the sewing machine illustrated in Figs. 1 and 2.

Fig. 4 is the other end view of the sewing machine illustrated in Figs. 1 and 2.

Fig. 5 is a side view of the tape or binding reel supports.

Fig. 6 is the front view of the tape or binding reel supports.

Fig. 7 is a fragmentary top view of the fabric presser foot.

Fig. 8 is a sectional view taken along the line 8—8 of Fig. 7.

Fig. 9 is a sectional view taken along the line 9—9 of Fig. 7.

2

Fig. 10 is a plan view of the tape guide.

Fig. 11 is a side view of the tape guide taken along the line 11—11 of Fig. 10.

Fig. 12 is an end view of the tape guide taken along the line 12—12 of Fig. 10.

Fig. 13 is a bottom view of the tape guide.

Fig. 14 is a plan view of an appliquéd as made on the machine embodying my invention.

Fig. 15 is another specimen of appliqués as made on the machine embodying my invention.

Fig. 16 is a section view taken on the line 16—16 of Fig. 14.

Referring now in detail to the drawings, I show in Fig. 1 a sewing machine wherein a plurality of pieces of tape or binding are symmetrically laid upon the surface of a fabric to form appliqués and wherein a plurality of parallel rows of stitches fasten the tapes or bindings to the fabric.

The sewing machine which comprises a hollow machine frame or casing, generally designated as 20, has a needle bar 20 that carries a plurality of sewing needles 22 in a needle support 24, see Figs. 1, 2, and 3. A presser bar 26, see Figs. 7, 8, 9, located behind the needle bar 20 reciprocates vertically in the customary manner by the customary sewing machine mechanism (not shown). The presser bar carries a foot 26' having an opening 28' therein through which the sewing needles 22 operate. A guide 29 for guiding tape 34 extends across the presser foot 26' in front of the sewing needles for a purpose to be hereinafter described. Each needle 22 sews a row of stitches which may be chain stitches or lock stitches.

A throat cloth plate 30, mounted upon a horizontal work support 32, has suitable slots therein through which operate rows of teeth of a feed dog (not shown) to feed the fabric or work, off or towards the rear of the work support 32, the work passing over the throat plate 30, and under the presser foot.

Two reels 35, 35 of tape or binding 34 are suitably mounted on a bracket 36, which bracket may be attached to the frame A.

The reels 35 are under some tension by virtue of springs 37 thereon to prevent undue unwinding of the reels of tape, see Figs. 5 and 6.

The tape or binding 34 is fed into guides, generally designated as B and B1, see Figs. 3, 10 to 13 inclusive, which may turn the side edges of the tape to overlap in order to present a neater appearance to the tape or binding, or in the event the edges of the tape are unbound so that the sides are overturned to prevent the fraying of the tape or binding.

Each of the guides B and B₁ comprise a tapered tunnel 36, whose free end bore 38 is elliptical and whose fixed end bore 40, although elliptical, is of smaller size than the free end bore. At the longitudinal center of the bore are upturned curved guides 42, 44 which overturn the sides of the tape or binding, so that when the fixed end bore 40 of the guide B is reached the sides of the tape or binding are overlapping the central portion of the tape 34. The curved guides 42, 44 are cut from the body of the guide and are preferably integrally formed therewith although they may be made of a separate piece and attached to the guide B, B₁. Suitable mechanism, hereinafter described in detail, moves the guides B and B₁ parallel to one another crosswise of fabric or work but in opposite directions, that is to say, guides B and B₁ move together simultaneously and away from one another simultaneously when the guides are laying the tape or binding upon the fabric to form an appliquéd design. Hence, as the guides B and B₁ move in and out sideways of the fabric they lay curved appliquéd strips which are symmetrically balanced with respect to a center line. The plurality of needles 22 then sew in the customary manner a series of parallel rows of stitches through the tape 34 and the fabric.

Guide moving mechanism

The mechanism for moving the guides is as follows:

Guide B is supported on a bight portion 46, which is in front of the sewing needles 22, of a U-shaped bracket whose ends 48, 50 are attached to a horizontally positioned, rectilinear movable rod or shaft 52 supported in bearings 54, 54 carried by rear side of the frame. The rod 52 moves in a rectilinear direction in bearings 54, 54.

The second guide B₁ is supported on a bight portion 56, which is in front of the sewing needles 22, of a U-shaped bracket whose ends 58, 60 are attached to a horizontally positioned, rectilinearly movable rod 62 that is carried in bearings 54, 54, see Figs. 1, 2 and 3. The shafts or rods 52 and 62 are mounted parallel to one another and they reciprocate in opposite directions, thereby moving the guides B and B₁ in opposite directions.

Means to move guide moving mechanism

The guides B and B₁ are adapted to move in opposite directions by virtue of the movement of the horizontally supported shafts 52 and 62 in the bearings 54.

The shafts 52 and 62 are moved in opposite rectilinear directions by the following described mechanism:

The main shaft 66 of the sewing machine passing through the frame A of the sewing machine is rotated by either foot or electric motor (not shown) and the shaft 66 has a worm gear 68 thereon. A large gear 70, supported on a shaft 72, carried by bearings 74, 74, is coupled to and driven by worm 68, see Fig. 4. The gears 68 and 70 are mounted at right angles to one another.

Upon one end of the shaft 72, to the rear of the frame A, a spur gear 76 is rotatably mounted and the gear 76 has coupled thereon an adjustable eccentric 78 which is pivoted to a slide 80 that may be tightened by a screw 82. Adjustment of the eccentric 78 away or towards the center of the shaft 72 determines the lateral distance that the guide B moves or oscillates, see Fig. 2. The eccentric 78 has pivoted thereto one end of a throw

or crank arm 84, and one end of the second part of the crank arm, that is, crank arm 84A is pivotally connected to a pivot 86 on the horizontally movable shaft 52. The crank arm is made of two parts 84 and 84A coupled by a joint 88, for ease of assembly or disassembly.

A spur gear 90 of the same diameter as spur gear 76 is coupled to spur gear 76 in the same plane and rotates in the opposite direction to spur gear 76 and at the same rate of speed. Spur gear 90 is coupled to drive the shaft 62 in the opposite direction to movement of the shaft 52. A similar type of mechanism between spur gear 90 and shaft 62 is used as between spur gear 76 and shaft 52—so that a detailed description of only one set of driving and coupling need be given as the same description and numbering of elements applies to both.

Hence, if the guide B₁ is to be adjusted so that the length of oscillation is to be changed the eccentric 78 on gear 90 is moved either closer to or farther from the center of the gear 90.

The guide B is attached to the horizontal bight portion 46 by screws so that the small end of the funnel 40 is aligned with an opening 92 in the bight portion and the guide B₁ is attached in an analogous manner so that the small opening of the funnel connects with opening 94 in the bight portion 56. Since the appliquéd work may have the tapes meet at the center it is necessary to have one tape guide B higher than the other but the tape or binding which comes from the guides is applied to the surface of the fabric or work at an even level by virtue of the guide 29 on the presser foot 26.

A description of the operation of my invention will serve to illustrate the function and cooperativeness of the elements constituting my invention:

40 The tapes 34, 34 are hung on reels which are carried by the bracket 36 and the tapes are fed through funnel guides B and B₁. I shall assume that the tapes are to have their side edges overlapping the body of the tape and this is performed when the tapes pass through the tunnels. A series of sewing needles 22 have thread T through their eyes and the work or fabric F is laid upon the base 32 of the machine under the presser foot 26'. The eccentrics 78 on gears 76 and 90 are properly adjusted so that the guides B and B₁ oscillate the required distance. After the adjustments are completed the sewing machine is operated and as the rows of stitches are formed in a straight line they attach the undulatory or wavy tape 34 to the fabric F, see Figs. 14 and 15.

The undulations of the tapes 34 are brought about by the guides B and B₁ oscillating.

60 If different degrees of undulations are desired then the eccentrics may be moved to produce overlapping undulations, spaced undulations, single undulations by using only one cam and one guide, and even rick-rack may be used to be guided upon the fabric or work, see Figs. 14, 15.

Although my invention has been described in considerable detail, such description is intended as illustrative rather than limiting, since the invention may be variously embodied and the scope of the invention is to be determined as claimed.

I claim as my invention:

1. A sewing machine comprising stitch forming mechanism operable to form a plurality of rows of stitches, a drive shaft on said sewing machine, a worm gear mounted on said drive shaft,

a spur gear cooperatively engaging said worm gear and mounted on a shaft, a second spur gear mounted on the same shaft as said first named spur gear, a third spur gear meshed with said second spur gear, an eccentric on each of said meshed spur gears, means to adjust each eccentric, a connecting link having one end thereof connected to each eccentric, a horizontally movable shaft connected to the other end of each connecting link, and brackets fixed to said movable shafts and carrying tape guides, said tape guides being movable with said brackets and said movable shafts.

2. A sewing machine comprising a stitch forming mechanism including a plurality of sewing needles, a presser foot having a needle opening and a tape guide, a plurality of brackets movable parallel to the common plane of said sewing needles, a funnel shaped tape guide detachably secured to each bracket, each of said brackets having a bore contiguous to the egress bore of said funnel shaped tape guide, and means to oscillate said brackets during the stitch forming operation.

3. A sewing machine comprising a stitch forming mechanism including a plurality of sewing needles, a presser foot having a needle opening and a tape guide, a plurality of brackets movable parallel to the common plane of said sewing needles, a funnel shaped tape guide detachably secured to each bracket, each of said brackets having a bore contiguous to the egress bore of said funnel shaped tape guide, and means for

moving each of said brackets in opposite directions during the stitch forming operation.

4. A sewing machine comprising a stitch forming mechanism including a plurality of sewing needles, a presser foot having a needle opening and a tape guide, a plurality of brackets movable parallel to the common plane of said sewing needles, a funnel shaped tape guide detachably secured to each bracket, each of said brackets having a bore contiguous to the egress bore of said funnel shaped tape guide, means for oscillating said brackets during the stitch forming operation, and means to control the oscillatory movement of each bracket.

WALTER HARPHAM.
